UNITED STATES PATENT OFFICE.

ARTHUR J. DAANE, OF CHICAGO, ILLINOIS.

VIBRATOR FOR PRINTING PRESSES.

Application filed October 18, 1921. Serial No. 507,483.

To all whom it may concern:

Be it known that I, ARTHUR J. DAANE, citizen of the United States, residing at Chicago, in the county of Cook and State 5 of Illinois, have invented a certain new and useful Improvement in Vibrators for Printing Presses, of which the following is a full, clear, concise, and exact description, reference being had to the accompanying 10 drawings, forming a part of this specification.

The invention relates to ink distributing rollers for printing presses, and particularly to a means for quickly and conveniently 15 permitting the attachment and removal of the device to and from the printing press and to provide a construction whereby this may be accomplished without necessitating any change to be made to the press.

It is an object of the invention to provide a construction capable of performing the above advantages which is simple and effective in construction and operation which may be removably clamped to the 20 inking roll frame which in one type of press carries the inking rolls and travels in planes across the platen and type, this portion to which the distributing roll is removably attached being termed the saddle.

It is a further object of the invention to provide a construction which is movable outwardly relatively to the ends of the distributing roller, so that it may be arranged 25 in this position to permit of its attachment or release with respect to the saddle.

It is a further object to provide the device with means for releasably locking the parts against accidental release when associated for use with the press.

In the particular embodiment or structure employed for accomplishing the desired advantage one of the elements is movable outwardly with respect to the ends of 45 the distributing roller, so as to permit this part to be arranged to allow the end of the roller and the device to be associated with the saddle. Upon the release of this movable portion, the saddle is engaged, and 50 this portion engages certain other parts of the construction, in which position it is releasably locked against accidental separation.

The invention will be explained in 55 conjunction with the accompanying drawings in which various structures are illustrated,

it being, therefore, obvious that other changes and modifications may be resorted to without departing from the spirit of the appended claims forming part hereof. 60

In the drawings, Figure 1 is a side elevation of a portion of the printing press having one embodiment of the invention applied thereto.

Figure 2 is an elevation partially in section of an ink distributing roll showing the embodiment of the structure shown in Figure 1.

Figure 3 is an end view of the structure shown to the left of Figure 2.

Figure 4 is a view showing one of the structures employed in Figure 2, in changed position.

Figure 5 is an end elevation of the structure shown at the right of Figure 2.

Figure 6 is a sectional view of a modified arrangement which may be resorted to showing a changed position in dotted lines.

Figure 7 is an end elevation of another structure which may be employed to accomplish the invention.

Figure 8 illustrates a tensioning device for the ink distributing roller, which may be applied to the end of the previous structures.

Figures 9, and 10 illustrate further construction which may be employed to accomplish the invention.

In the embodiment of the invention illustrated in Figure 2 the use of a roller 90 10 is contemplated which reciprocates longitudinally of the shaft 11. This roller cooperates with the usual inking rollers of the press and due to its reciprocation evenly distributes the ink upon the aforesaid 95 rollers thereby insuring even distribution of ink upon the type.

The means whereby this device may be attached to a printing press without necessitating any changes being made to the 100 press or the use of any tools to effect its attachment and release, is generally designated 12 and consists of two members, 13 and 14, which are designed to embrace the saddle 15 of the press to hold the ink distributing roller with relation to the press. The member 12 is bent to form the right angle portions 16 and 17, the end of the portion 16 being bifurcated to provide the arms 18—18 between which the member 13 105 is pivotally mounted so that it may swing outwardly with respect to the shaft 11 when

the parts entering into this construction are arranged to permit of this.

The downwardly extending portion 17 of the member 12 is provided with a slotted aperture 18^a which receives the shaft 11 and permits it to reciprocate with respect to the member 14 to thereby compensate for various shaped surfaces over which the inking rollers of the press travel during their movement relative to the platen of the press and the type.

The shaft 11 extends beyond the downwardly extending portion 17 of the member 12 and slightly beyond the swinging member 13 and is provided with a head 19 and a reduced or neck portion 20, the reduced portion substantially corresponding in dimensions to a reduced portion of a slot provided in the member 13 in which the shaft is mounted for reciprocation. This slot is designated 21 and is provided with an enlarged portion 22 with which the end of the shaft is brought into juxtaposition thereby permitting the member 13 to be disconnected from this end of the shaft 11 when swung outwardly. This enlarged portion of the slot permits the connection of the swinging member 13 when the latter is swung inwardly and the enlarged end of the slot and end of the shaft are again brought into register.

This member 13 is provided with a handle or finger piece 23 to assist in swinging the member 13 outwardly. A coiled spring 24 is provided which engages this member 13 adjacent the handle and acts to swing the lowermost portion of the member 13 inwardly when the pressure upon the handle 23 is released, the coiled spring being arranged upon the pin 25 which passes through the member 13 and into the bifurcated ends 18—18.

A plunger 26 is connected at 27 to the shaft 11. This plunger passes through the part 14 of the member 12 and into a housing 28 within which is confined a spring 29 which reacts between a shoulder provided on the plunger and an end of the housing 28. This maintains the shaft 11 and the roller 10 in close contact with the inking rolls and saddles of the press yet permits it to yield or reciprocate within the slots 18 and 21.

The lowermost end of the member 13 is provided with an inwardly projecting lug 30 which has a curved surface which when the device is arranged in proper relation with respect to the saddle of the press, is permitted to engage one of the lower faces of the saddle and allows the device to rock with relation to the saddle. A portion of the arm 17 engages one side face of the saddle, the member 13 the opposite side and the end of the shaft is arranged adjacent the uppermost face thereof, consequently the

saddle is confined when the device is arranged for use with respect to the press.

To effect a separation of the device and the roller 10 from the saddles of the press, pressure will be applied to the members 12 and 13 depressing them until the end of the shaft 11 is arranged adjacent the portion 16 of the member 12. This brings the extreme end of the shaft having the head 19 and the neck 20 into relation with the enlarged portion 22 of the slot 21 so that an inward pressure applied to the finger piece 23 permits the lowermost end of the member 13 to be swung outwardly away from the end of the shaft which disassociates these members and permits the entire device and the inking roller to be lifted away from the press.

To effect a connection of the roller and this element and the press the device will be arranged above the saddle and pressure again applied until the extreme end of the shaft is brought into alignment with the enlarged opening 22 of the aperture 21 of the member 13 and by virtue of the action of the spring 24 the member 13 is moved toward the extremity of the shaft over the head 19.

Upon the release of the downward pressure heretofore referred to the members 12 and 13 are moved upwardly and the shaft is moved in the opposite direction by means of the spring 29 causing the shaft 11 to assume a position adjacent the lowermost extremity of the slot 21. By virtue of the shape of the extremity of the shaft 11 and the slot with which it is at this time in co-operative relation, the parts are locked together so that accidental separation thereof is prevented, it being understood that at this time the inward extension 30 is in engagement with the lower face of the saddle.

The member 13 may, if so desired, be provided with the lugs 31 which are designed to engage the side faces of the portion 33 of the saddle.

From the description of this structure it is evident that a simple and effective means is provided for attaching and removing an ink distributing roller to a printing press without necessitating any change or addition to be made to the press which is a material advantage as it eliminates much unnecessary labor.

It is understood that the opposite ends of the shaft are provided with a structure similar to that just described, however, provision may be made to permit the connection of a device of this character with the press despite the fact that the swinging frame of most presses of the Gordon type are provided with a pin whereby the pressman may manually lift or lower the inking rollers when this is found necessary or desirable. To accommodate this structure the

swinging member 13 will be provided with a cutout portion 34 which will readily pass over this pin or a structure similar to it which allows the device to be attached or 5 removed with relation to the press without hindrance by this pin.

In the structure illustrated in Figure 6, a slightly different arrangement is provided. In this embodiment of the invention the 10 clamping element, generally designated 35, is also movable outwardly and inwardly with respect to the end of the vibrator shaft to effect a separation and connection of the device and the press.

15 To accomplish this result when a structure similar to that illustrated in this embodiment of the invention is employed, the plunger 36 and the member 35 are movable together longitudinally of the shaft of 20 the vibrator in the slot 37 provided in the vibrator shaft.

A coiled spring 38 is confined in this slot 37 and this spring reacts between the end of the slot and the reduced portion 39 of the plunger. The plunger is provided with an enlargement 40 at its lowermost end and the fact that the remainder of the plunger 36 is of a greater dimension than the slot 25 prevents the separation of the plunger and the shaft, but permits the plunger to slide longitudinally within the slot 37. The member 41 in this structure is provided with a slot 41^a within which the end of the vibrator shaft is mounted for reciprocation with 30 relation to the member 41. This slot also permits the member 35 and the plunger to be moved longitudinally of the vibrator shaft so as to position the member 35 to allow it to engage and release the saddle of the inking rollers of the press.

40 The inwardly projecting portion 42 of the member 41 is provided with a housing 43 within which is confined a coiled spring 44 which acts upon the plunger 36 in a manner 45 similar to that described with relation to the structure disclosed in Figure 1, and allows the plunger to be moved with relation to said bracket.

From the description of this structure it 50 is evident that the plunger 36 and the member 41 may be moved together endwise or longitudinally with relation to the end of the shaft which permits the device to be positioned to allow it to engage and release 55 the saddle of the printing press when manipulated to accomplish this result.

The shaft of this structure has a pin 45 projecting from the under surface thereof which is provided to engage the innermost face of the saddle.

60 The member 41 is also provided with an inwardly projecting lug 46 and the lugs 47-47 which respectively engage the under and opposite sides of the projection 33^a of the saddle. This structure may also be

provided with a cut away portion 48, the function thereof being similar to the portion 34 shown in Figure 2.

It is manifest that this structure is also capable of effecting an association and release of the distributing roll and press by the application of an outward pressure upon the member 36 or 41 which will position the parts to allow the device to be associated and disconnected relatively to the press. 70 Upon the application of this pressure the inwardly projecting lugs 46 and 47 are positioned relatively to the saddle so that by a downward pressure upon the member 35 the lugs 46 and 47 will be brought to a 75 position in which they may engage the lower face of the saddle. Upon the release of the outward pressure upon these aforesaid elements the spring 37 causes said lugs to pass below the lower face of the saddle and upon the release of the downward pressure upon the member 35 the coiled spring 44 is permitted to act which brings the lugs into engagement with the underside of the saddle 80 and the shaft into engagement with the upper face thereof.

To effect a separation of the structure after it has been applied, all that is necessary is to apply an outward pressure to the plunger 36 or the member 35 and its associated mechanism. This causes a disconnection of the lugs 46 and 47 from the saddle 85 which allows the entire mechanism to be lifted away from the press.

In the structure shown in Figure 10 the 90 vibrator shaft is provided with two pins 52 which when the device is arranged for cooperation with the saddle of the press, are disposed upon opposite sides of the swinging portion of the structure. This allows 95 the shaft to reciprocate in its slot, the latter being enlarged at its uppermost end to allow the swinging member to be moved beyond the end of the shaft.

All of these structures, heretofore explained, may, if so desired, be provided with a means for regulating the tension of the spring which acts upon the plungers such as 36 which are connected to the shafts of the distributing roller. To accomplish this 100 advantage the outer face of the housings for the spring will be provided with screw threads 53 and arranged in threaded relation to the portion carrying the housing. By rotating the housing by means of the head 54, said housing will be adjusted and vary the tension of the springs confined therein. This structure may be provided with a set nut 55 to lock the housing in its 105 adjusted position with relation to the particular element with which it is associated.

In the structure illustrated in Figures 9 and 10, the swinging portions are pivoted to the shaft at 56, and arranged to swing 110 from this point as a pivot. The structure of 115

Figure 9 is slightly different from that of Figure 10 in that a vertically arranged pin 57 is carried by the swinging member 58. This pin 57 enters an aperture 59 in the shaft of the vibrator. This end of the shaft is arranged for reciprocation with respect to the pin 57 and the slot 60.

To disconnect the means of this structure, the shaft will be moved to assume the dotted line position shown. This allows the member 58 to be swung outwardly upon the pivot 56 causing the disconnection of the parts and allowing either the association or removal of this device from the saddle of the printing press.

From the foregoing description of the various structures, it is evident that a simple and effective arrangement is produced whereby an ink distributing roller may be 20 releasably connected to the frame of a printing press by a movement which is endwise of the distributing roller shaft; also that provision is made whereby said roller may be moved with relation to the saddle during 25 its travel with the inking rolls of the press without resulting in a disconnection or the device whereby the distributing roller and the press are connected together. It is further evident that the device may be attached to a printing press without necessitating 30 any change whatsoever to be made in the construction of the press, despite the fact that in some instances a pin or other projection is part of the printing press structure.

Having thus described the invention what I claim and desire to cover by Letters Patent is:

1. In a device of the class described the combination of an ink distributing roller and means for permitting said roller to be releasably mounted with respect to a printing press, said means being movable longitudinally with respect to the roller while in associated relation with said roller to effect an attachment of the roller and press.
2. In a device of the class described, the combination of an ink distributing roller and means for permitting said roller to be releasably mounted with respect to a printing press, said means being movable longitudinally with respect to the roller while in associated relation with said roller to effect a release of the roller and press.
3. In a device of the class described, the combination of an ink distributing roller and means for permitting said roller to be releasably mounted with respect to a printing press, said means being movable longitudinally with respect to the roller while in associated relation with said roller to effect an attachment and release of the roller and press.
4. In a device of the class described, the combination of an ink distributing roller and

means carried by the roller for permitting said roller to be releasably mounted with respect to a printing press, said means being movable longitudinally of the roller to effect an attachment of the roller and press and including a tensioning device.

5. In a device of the class described, the combination of an ink distributing roller and means for permitting said roller to be mounted with respect to a printing press, 75 said means including a member which is movable lengthwise and transversely of the roller.

6. In a device of the class described, the combination of an ink distributing roller and 80 means for permitting said roller to be mounted with respect to a printing press, said means including a member which is movable lengthwise and yieldable transversely of the roller.

7. In a device of the class described, the combination of an ink distributing roller and means for permitting said roller to be mounted with respect to a printing press, 90 said means including a member which is movable lengthwise and transversely of the roller and tensioning means associated with said means.

8. In a device of the class described, the combination of an ink distributing roller and means for permitting said roller to be 95 removably attached to the saddle of an inking roller, said means permitting said distributing roller to be clamped to said saddle and including means movable lengthwise and transversely to the roller, said means also including means for locking said first mentioned means against lengthwise movement.

9. In a device of the class described, the 105 combination of an ink distributing roller and means for permitting said roller to be removably attached to the saddle of an inking roller, said means permitting said distributing roller to be clamped to said saddle and including means movable lengthwise and transversely to the roller, said means also including means for locking said first mentioned means against lengthwise movement, said locking means permitting the distributing roller to be moved relatively to said first mentioned means when in locked relation to the saddle.

10. In a device of the class described, the combination of an ink distributing roller and means for permitting said roller to be 110 removably attached to the saddle of an inking roller, said means including means for engaging the side faces of said saddle and a member which is movable outwardly with 115 respect to the end of said distributing roller.

11. In a device of the class described, the combination of an ink distributing roller and means for permitting said roller to be 120 removably attached to the saddle of an ink-

ing roller, said means including means for engaging the side faces of said saddle and a member which is movable outwardly and transversely with respect to the end of said distributing roller.

12. In a device of the class described, the combination of an ink distributing roller and means for permitting said roller to be removably attached to the saddle of an inking roller, said means including means for engaging the opposed side faces of said saddle and a member which is movable outwardly with respect to the end of said distributing roller.

13. In a device of the class described, the combination of an ink distributing roller and means for permitting said roller to be mounted with respect to a printing press, said means including a member which is movable lengthwise and transversely of the roller, and means permitting said roller to move relatively to the press when attached thereto.

14. In a device of the class described, the combination of an ink distributing roller having means arranged adjacent its end for permitting said roller to be mounted with respect to a printing press, said means including a member which is movable lengthwise and transversely of the roller and being manually movable in one direction and automatically movable in the opposite direction.

15. In a device of the class described, the combination of an ink distributing roller, having means mounted thereon adjacent its end for permitting said roller to be mounted with respect to a printing press, said means including a member which is movable endwise of the ink distributing roller, said member being manually movable in one direction and automatically movable in the opposite direction.

16. An inking roller for printing presses having means pivotally associated with an end of said roller whereby said roller may be removably attached to a printing press.

17. An inking roller for printing presses having means pivotally associated with an end of said roller whereby said roller may be removably attached to a printing press, said means permitting said roller to move relatively to the press when associated with said press.

18. An inking roller for printing presses having means associated with an end of said roller whereby said roller may be removably attached to a printing press, said means being movable endwise of said roller and having means for engaging said press.

19. An inking roller for printing presses having means associated with an end of said

roller whereby said roller may be removably attached to a printing press, said means being movable endwise of said roller and having means for engaging said press and permitting said roller to move transversely to the axis of said roller.

20. An inking roller for printing presses having means associated with an end of said roller whereby said roller may be removably attached to a printing press, said means being movable endwise and transversely of the roller to permit of its association with said press and being movable transversely to the axis of said roller when associated with said press.

21. An inking roller for printing presses having means associated with an end of said roller whereby said roller may be removably attached to a printing press, said means being movable endwise of said roller and having means for engaging said press, said last mentioned means permitting said roller to rock relatively to the press when associated with said press.

22. An inking roller for printing presses having means associated with an end of said roller whereby said roller may be removably attached to a printing press, said means being movable endwise of said roller and permitting said roller to rock relatively to said press when associated with said press.

23. An inking roller for printing presses having means associated with an end of said roller whereby said roller may be removably attached to a printing press, said means being movable endwise of said roller and having means for engaging said press and permitting said roller to move transversely to the axis of said roller, and to rock relatively to the press when associated with said press.

24. In a device of the character described, the combination of an inking distributing roller having means permitting said roller to be removably attached to a printing press, said means including a bracket secured to the end of said roller, a member pivotally secured to said bracket, said member having means for engaging said press, a spring for releasably holding said member in engagement with bracket, having means permitting said roller to be moved relatively to the bracket to permit of the association and removal of said roller relatively to the press and said bracket permitting movement of said roller relatively to the bracket when associated with said press.

In witness whereof, I hereunto subscribe my name this 10th day of October, A. D. 1921.

ARTHUR J. DAANE.
